His Attorney

UNITED STATES PATENT OFFICE.

EUGENE G. WESSON, OF LINCOLN, NEBRASKA, ASSIGNOR TO THE UNION SWITCH & SIGNAL COMPANY, OF SWISSVALE, PENNSYLVANIA, A CORPORATION OF PENNSYLVANIA.

RAILWAY-SWITCH-ACTUATING MECHANISM.

Application filed April 24, 1928. Serial No. 272,380.

My invention relates to railway switch actuating mechanisms, and has for an object the provision of means for actuating a railway switch by two separate and distinct devices, such, for example, as by a lever of an interlocking machine and by a hand-actuated ground lever.

I will describe one form of mechanism embodying my invention, and will then point out the novel features thereof in claims.

In the accompanying drawing, Fig. 1 is a diagrammatic view showing one form of switch actuating system to which the mechanism embodying my invention may be applied. Fig. 2 is a plan view of the mechanism B shown in Fig. 1, with the cover removed, which mechanism embodies my invention. Fig. 3 is a vertical sectional view of the mechanism shown in Fig. 1.

Similar reference characters refer to similar parts in each of the several views.

My invention constitutes an improvement on the mechanism shown in an application for Letters Patent of the United States by Edwin G. Little, Serial No. 202,273, filed June 29, 1927. In some instances mechanisms, of the type shown in the said Little application have been operated and controlled by the levers of a mechanical interlocking machine in such manner that one lever is mechanically connected with the bar 5 and another lever is mechanically connected with the shifter plate 11, so that normally the switch is actuated by the first interlocking machine lever, but the switch may be operably connected with the hand lever 1 by reversing the second machine lever. When the mechanism is used in this manner, I have found that after the shifter plate has been reversed to connect the switch with the hand lever 1, the compression which normally exists in the pipe line connecting the bar 5 with the first machine lever may throw this bar out of alignment with the shifting block 9, so that the mechanism cannot be restored to normal position by restoration of the second machine lever to its normal position because block 9 will not enter the recess in bar 5. One feature of my invention is the provision of means for locking the bar 5 in its normal position when the selecting apparatus is operated to place the mechanism in condi-

tion for operation of the switch by the hand lever 1.

Referring now to the drawing, the reference character B designates a mechanism comprising a suitable box or casing 45, which is provided with guides to accommodate three parallel longitudinally movable bars 3, 4 and 5. The bar 4 is operatively connected with a railway switch A, and the bar 5 is operatively connected by a pipe line 48 with a switch actuating lever L¹ of an interlocking machine. The bar 3 is operatively connected with a manually operable ground lever 1 through the medium of a miter gear 23, a second miter gear 24, and an arm 26 which is pivotally connected with the bar 3. Located within the mechanism case 47 is a shifter plate 11 mounted to slide longitudinally in a direction perpendicular to the direction of movement of the bars 3, 4, and 5. The right-hand end of this shifter plate is provided with a slot to receive two blocks 9 and 10 which coact with recesses cut in the under sides of the bars 3, 4 and 5. When the shifter plate is in its left-hand position, in which it is shown in the drawing, block 10 cooperates with bars 4 and 5 to connect these bars for simultaneous movement. It follows that under this condition switch A can be actuated by the interlocking machine lever L¹. When the shifter plate 11 is moved to its right-hand position, the block 10 releases bar 4, and bars 3 and 4 are then operatively connected by block 9 for simultaneous movement. The apparatus is then in condition for actuation of the switch A by the hand lever 1.

The parts of the apparatus thus far described, are substantially the same as the corresponding parts in the application of E. G. Little, referred to hereinbefore, and consequently, detailed explanation of the structure and operation of these parts is not essential in the present case.

In the present disclosure the shifter plate 11 is actuated by a fourth bar 41, which is mounted to slide longitudinally in suitable guides formed at the left-hand end of the casing 45. This bar 41 carries a cam 43 coacting with two blocks 42 and 44 attached to the shifter plate 11, the co-action being such that longitudinal movement of the bar

41 causes operation of the shifter plate to its right and left-hand positions. With the parts in the positions in which they are illustrated in the drawing, the shifter plate is 5 in its left-hand position. When the bar 41 is pushed inwardly, cam 43 coacts with block 42 to move the shifter plate to the right, and when the bar 41 is again returned to its 10 illustrated position, cam 43 coacts with block 44 to move the shifter plate to the left. The bar 41 is connected by a pipe line 49 with the selector lever L^2 in the interlocking machine.

The shifter plate 11 actuates a circuit controller C through the medium of a slotted yoke 33, a crank 32, a shaft 31, and a pair of miter gears 34 and 35. The circuit controller and the apparatus for operating it, have nothing to do, however, with my present invention.

Located in the right-hand end of the mechanism case 45 is a plate 37 having two notches 37^a and 37^b. The notch 37^a is in such position as to receive the block 10 when 25 this block is shifted to the right to disconnect bar 5 from bar 4. When the block 10 is in its right-hand position, it occupies the notch 37^a and also the recess in the underside of bar 5, so that bar 5 is locked in its 30 proper position, with the result that when the shifter plate is restored to its left-hand position, block 10 will enter the recess in the underside of bar 4. The parts are so 35 adjusted that during right-hand movement of the shifter plate 11, the block 10 enters the notch 37^a before it leaves the recess in bar 4. It will be seen, therefore, that after 40 the selector lever L^2 has been reversed to place the mechanism in condition for ground lever operation of the switch, the bar 5 is located in its normal position in spite of the tendency of the compression in pipe 48 to throw this bar out of its normal position.

The notch 37^b in the plate 37 is merely 45 for use when the relative positions of the switch and the mechanism shown in Fig. 1 are reversed.

The plate 37 may be mounted in the case 45 in any suitable manner. As here shown, this plate is provided with slotted holes to receive bolts 38 by which the plate is attached to the bottom of the casing, and the plate is further provided with two upstanding lugs 39 threaded to receive tap screws 40 50 which coact with the two side walls respectively of the case. The plate 37 is adjusted to the proper position by means of the set screws 40, and is then locked in such position by tightening the bolts 38.

60 Although I have herein shown and described only one form of mechanism embodying my invention, it is understood that vari-

ous changes and modifications may be made therein within the scope of the appended claims without departing from the spirit and 65 scope of my invention.

Having thus described my invention, what I claim is:

1. Railway switch actuating mechanism comprising two separate and distinct devices 70 for actuating the switch, apparatus for selectively connecting the switch with one or the other of said devices, and means for locking one of said actuating devices while the other actuating device is connected with the switch. 75

2. Railway switch actuating mechanism comprising two separate and distinct devices for actuating the switch, a bar operatively connected with the switch, a second bar operatively connected with the first actuating device, a third bar operatively connected with the second actuating device, means for selectively connecting said first bar with said second bar or said third bar, and a device associated with said selecting means for 80 locking the second bar while said third bar is connected with said first bar. 85

3. Railway switch actuating mechanism comprising a casing containing three parallel longitudinally slidable bars, the first of 90 which is operatively connected with the switch, the second of which is operatively connected with one actuating device and the third of which is operatively connected with a second actuating device, said bars 95 having registering notches, a shifter plate slidably transversely with respect to said bars, a pair of blocks slidably mounted in said shifter plate and coacting with the notches in said bars, a notched locking plate 100 fixed in said casing, and means for moving said shifter plate to one position wherein the first block operatively connects the first and second bars, and to another position wherein the second block operatively connects the first and third bars and the first block coacts with both the notch in the first bar and the notch in said locking plate. 105

4. Railway switch actuating mechanism comprising a bar operatively connected with 110 the switch, a second bar mechanically connected with an actuating lever of an interlocking machine, a third bar operatively connected with a ground lever, means including a selector lever of said interlocking 115 machine for selectively connecting said first bar with said second bar or with said third bar, and a device associated with said last mentioned means for locking said second bar while the third bar is connected with the 120 first bar.

In testimony whereof I affix my signature.

EUGENE G. WESSON.
